SUPPORT LEG FOR ELEVATED TOILET SEAT

William R. Brewer, Arleta, Calif., assignor to Hamilton C. de Jong (doing business as Safety Brothers), Pasadena, Calif.

Original design application Apr. 22, 1970, Ser. No. 22,557. Divided and this application Oct. 13, 1971, Ser. No. 189,076

Term of patent 14 years

Int. Cl. D23—02

U.S. Cl. D23—71

FIG. 1 is a front perspective view of a support leg for an elevated toilet seat showing my new design;
FIG. 2 is a left side elevational view of the same;
FIG. 3 is a front elevational view;
FIG. 4 is a right side elevational view;
FIG. 5 is a top plan view; and
FIG. 6 is a bottom plan view.

The broken line representation of an elevated toilet seat in FIG. 1 is for purposes of illustration only.

This is a division of design application Ser. No. D. 22,557, filed Apr. 22, 1970, now abandoned.

I claim:

The ornamental design for a support leg for an elevated toilet seat, as shown and described.
